UNITED STATES PATENT OFFICE.

MASCHIL D. CONVERSE, OF YONKERS, NEW YORK.

SNAP-HOOK.

SPECIFICATION forming part of Letters Patent No. 340,558, dated April 27, 1886.

Application filed June 16, 1884. Serial No. 134,953. (Model.)

To all whom it may concern:

Be it known that I, MASCHIL D. CONVERSE, a citizen of the United States, residing at Yonkers, in the county of Westchester and State 5 of New York, have invented new and useful Improvements in Snap-Hooks for Harness and for other Purposes, of which the following is a specification.

The object of my invention is to provide a snap-hook which will under all circumstances maintain a grasp of the ring or other object to which it is hooked, but which can be instantly attached or detached when required. I attain this, as will be more clearly understood by 15 reference to the accompanying drawings, forming part of this specification, first, by constructing my snap-hook in two similar parts or halves, the one inverted upon the other and secured by a pivotal rivet; and, second, by 20 the use of branches, branching off from the shanks and extending beyond and at or about right angles to the point of the hook of each of the halves, which together are adapted to 25 keep the snap-hook from becoming accidentally disengaged from the ring, as will hereinafter appear.

In the drawings, Figure 1 is a side view of my snap-hook complete, caught upon a ring, the dotted lines showing various positions of 30 the same respectively, the thumb and index-finger of the hand represented in the same figure showing the manner of grasping the snap-hook when required to disengage it from the ring; Fig. 3, a side view of one half of the snap-hook, the dotted lines in the same figure showing accidental positions of the snap-hook and the ring; Fig. 2, an edge view of the halves of the snap-hook separated and the pivotal rivet.

Similar letters indicate corresponding parts in the several figures.

A is the shanks of the halves of the snap-hook, and B the branches; C, the hooks; D, the pivotal rivet; E, the eye; F, the stops; h^1 , h^2 h^3 h^4 h^5 , the ring in different positions, and H a position of the ring hereinafter referred to.

The operation of my snap-hook is as follows: Grasping it in the manner shown in Fig. 1, the lips G are pressed forward against the 50 ring h' , and opened to receive the latter by pressing the thumb and index-finger toward

each other, one of the halves of the snap-hook swinging off into the position shown by dotted lines in the same figure. When the ring comes to the position h^2 , and the stops F strike the 55 shanks A, a continued forward thrust causes the hook of the half before swung off to swing back again by the ring pressing into the fork of the branches B, where they cross each other, until the hooks C are in the position they 60 were when starting, and the ring has reached the position h^3 . Forward movement being now stopped, the hooks drop upon the ring, leaving the latter in the position shown by H. It will be observed that forward pressure against 65 is the only condition required to attach the snap-hook to the ring. Now, to detach it, it may be either pushed steadily forward against or held slightly taut on the ring, the latter being the preferable method; but two other 70 conditions are also necessary, and must be simultaneous with the former before it can be disengaged, as will appear. Therefore to detach the snap-hook from the ring, grasp it in the manner shown in Fig. 1, with the thumb 75 and the index-finger, respectively, upon the stops F; pull the snap-hook slightly on the ring; then press the thumb and finger toward each other quickly. This causes the branches of the snap-hook to force the ring back toward 80 the hand till it will pass round the points of the hooks to the position h^4 and out. It is shown, therefore, that simultaneous pressure upon respective stops F, and the holding of the snap-hook taut on the ring, (to use the preferred method,) must occur before it can be 85 disengaged, as above stated, since, as shown in Fig. 3, if pressure be brought upon one side only—as, say, at the arrow—the ring would assume the position h^5 , and if continued till 90 the stops F reach the shanks A the branch of the opposite half of the snap-hook would lock the ring into the last-cited position, and then if pressure be brought to bear upon the other stop also, or simultaneously upon the 95 outside of the hooks at $y z$, the fork formed by crossing of the hooks at another point would force the ring from position h^5 around their points ultimately to the proper position, (shown by H in Fig. 1,) with the snap-hook in 100 the normal position. (Shown by the full lines in the same figure.)

In the manufacture of this snap-hook, if of cast malleable metal, the parts do not require to be seriously bent in the fitting; consequently the native strength is retained unimpaired.

5 Having described my invention, what I claim as new, and desire to secure by Letters Patent, is—

The improved snap-hook herein described,

consisting of the shanks A, secured by a pivotal rivet, D, provided with branches B, constructed and operating substantially as and for the purposes set forth.

MASCHIL D. CONVERSE.
